UNITED STATES PATENT OFFICE.

CORNELIUS VAN DYKE BENNETT, OF LIMA, NEW YORK, ASSIGNOR TO THE PORCELAIN INSULATOR CORPORATION, OF LIMA, NEW YORK, A CORPORATION OF NEW YORK.

INSULATOR-THREADING MACHINE.

Application filed October 10, 1923. Serial No. 687,781.

To all whom it may concern:

Be it known that I, CORNELIUS VAN DYKE BENNETT, a citizen of the United States of America, residing at Lima, in the county of

Livingston and State of New York, have invented certain new and useful Improvements in Insulator-Threading Machines, of which the following is a specification.

My invention relates to an insulator threading machine, more particularly of the general type in which a threading tool is moved downwardly into the central opening of an insulator or plastic body and then actuated horizontally to bring the tool into engagement with the adjacent surface of the insulator or plastic body, after which the parts are turned in suitable fashion to impress the thread upon the interior surface of the insulator.

A particular purpose of my invention is to afford simple and practicable mechanism for controlling the vertical and horizontal movements of the threading tool, so as to insure the latter reaching its lowermost position in the insulator before being moved horizontally, and vice versa on its withdrawal from the insulator.

A further object of the improvement is to afford means whereby the operator can very readily bring the threading tool into proper position with reference to the insulator, and yet with great accuracy, thereby insuring a high degree of perfection in the thread to be formed.

Still an additional and important feature of the invention is the provision of means for readily adjusting the extent of horizontal movement of the threading tool to a fine degree so as to adapt a machine readily, but with great efficiency, to insulators of different sizes or with different sized openings.

The invention also comprehends certain other advantages and detailed improvements, all of which will appear clearly from the following description when read in conjunction with the accompanying drawings, the novel features being pointed out in the claims following the specification.

In the drawings:

Figure 1 is a side elevation of an insulator threading machine, showing one adapta-

tion of the invention in a preferred embodiment, and with the threading tool in uppermost position;

Figure 2 is a similar view showing the position of the parts after the threading tool has been moved downwardly to its lowermost position with reference to the insulator, but before horizontal movement;

Figure 3 is an enlarged central sectional view of a portion of the machine, showing the position of the parts as in Figure 2;

Figure 4 is a sectional view similar to Figure 3, and showing the position of the parts after the threading tool has been moved horizontally to bring it into threading engagement with the wall of the insulator;

Figure 5 is a sectional view on the line 5—5 of Figure 3;

Figure 6 is a horizontal sectional view on the line 6—6 of Figure 3;

Figure 7 is a vertical sectional view on the line 7—7 of Figure 6, and

Figure 8 is a perspective view of one of the horizontally movable blocks which supports the threading tool.

Similar reference numerals throughout the several views refer to the same parts.

The structure of the present application is an improvement over that of my prior application Serial No. 572,337, filed July 1, 1922. In that prior application, the threading operation was effected by rotating the insulator, rotating the threading tool about its own axis, and also revolving the threading tool about the center of the insulator. In the structure of the present application, the revolving motion does not occur, and during the threading operation there are only two motions, namely, rotation of the insulator and rotation of the threading tool about their respective axes, and the novelty in the present case lies in the mechanism for imparting the necessary downward and lateral movements to the threading tool, to and from threading position, while the principal novelty of my earlier application resided in the mechanism for revolving the threading tool while at the same time rotating it about its axis.

Referring generally to Figures 1 and 2,

the mechanism which I have chosen as illustrative of one embodiment of the invention includes a base 1 and upright portion 2, while 3 is a rotary table or support for receiving the insulator 4 or other plastic body to be threaded. The support 3 is carried on a rotary vertical spindle 5 having keyed thereon a bevel pinion 6 driven by a bevel pinion 7 on the shaft 8. The latter is connected with vertical shaft 9 through bevel pinions 10 and 11, while 12 designates the main power shaft connected with the vertical shaft 9 by bevel pinions 13 and 14, power being imparted to the shaft 12 through the pulley 15 from any suitable source.

15 The threading tool includes a vertical shaft 20 having a threading member 21 at the lower end thereof for threading engagement with the insulator 4, as illustrated in Figure 20. The shaft 20 of the threading tool has splined thereon a sleeve 22 which carries preferably as an integral part thereof a bevel pinion 23, the latter engaging a cooperating bevel pinion 24 which is journaled in a bracket 25, and splined on the power shaft 14.

25 In the usual operation of the mechanism, an insulator is first positioned as in Figure 1, and power applied to the machine to rotate the threading tool and insulator, preferably at the same number of turns per minute. The threading tool is then moved downwardly as in Figures 2 and 3 to its lowermost position, following which it is actuated laterally into engagement with the wall of 30 the insulator, as shown in Figure 4, and when the thread is completed, the reverse movement takes place to withdraw the threading tool from the insulator. The parts for governing the vertical travel and 40 the means for effecting horizontal movements of the threading tool will now be described.

45 The horizontal actuating means includes generally a pair of blocks 26 and 27 in which shaft 20 is mounted for vertical sliding movement, said blocks having suitable guides or flanges 28 engaging guideways in the stationary arms 29 carried by the frame of the machine, while 30 is a stationary vertical plate connecting said arms 29. The aforementioned bracket 25 which carries bevel pinion 24 is fixed on the upper block 26 and movable horizontally with it, as will now be more fully explained.

55 The blocks 26 and 27 have pivoted thereto the links 35 which in turn are pivotally connected to bell crank levers 36, which are pivotally mounted on stationary lugs 37. 38 designates a control member in the form of 60 a rod pivotally connected to the outer ends of the bell crank levers 36, and 39 is a spring connected at one end to said rod 38 and at its other end to a stationary plate 40, and acting normally to move said rod 65 38 downwardly, as shown in Figure 4, and

thereby actuate the threading tool horizontally into threading engagement with the insulator.

The threading tool is controlled by an elevating device which includes a pulley 45 connected by a cable 46 to any suitable instrumentality for raising and lowering, while the devices connecting the threading tool with the horizontal actuating means includes a flexible member or cable 47 passing over said pulley 45 and connected at one end to the threading tool or vertical shaft 20, and at its opposite end to the rod 38. 48 designates a series of weights preferably arranged at the upper end of the shaft 20, whereby the threading tool drops by gravity when released, and 49 is a collar that is adjustably fixed on the shaft 20 and cooperates with a stationary collar 50 to limit downward movement of the threading tool.

55 With the parts related as just described, the threading tool is moved into operative position by first lowering the cable 46 and pulley 45 from the position illustrated in Figure 1 to that illustrated in Figure 2. 90 The weight of the threading tool and weights 48 being greater than the action of spring 39, causes the threading tool to move downwardly until the collar 49 strikes collar 50. The threading tool is then at the limit of its downward travel, and further lowering of the pulley 45 permits lowering of the rod 38 under the action of spring 39. The rod 38 thus moving downwardly operates the bell crank levers 36 and moves the blocks 100 26 and 27 horizontally, and with them the shaft 20, bringing the threading tool into operative or threading position, as shown in Figure 4. The return movement of the parts is accomplished by elevating the cable 105 46 and pulley 45, and the initial upward movement of these parts first causes the rod 38 to be moved upwardly, retracting shaft 20 to its central position, after which it is moved vertically out of the insulator.

110 It is particularly desirable and important to limit the horizontal movement of the threading tool accurately, and also to provide for a fine adjustment of such horizontal movement of the tool to accommodate 115 different sizes of insulators or different sized openings. This result is brought about by securing to the lower block 27 a stop plate 60 which engages a stop device 61 which may be controlled by a fine-adjustment mechanism. This is preferably accomplished by making the stop device 61 in the form of a wedge or tapered member, as illustrated in Figure 6, and slidable in guideways 62, see Figures 3 and 6. The stop device 61 has connected thereto a post 63, preferably swivelled to the stop device 61 and including a threaded portion 64 and dial plate 65, while 66 is a post having the threaded opening engaged by the stem 64. 67 is a knurled 120 125 130

head or finger piece mounted on the post 63, and 68 is a stationary scale cooperating with the dial plate 65 and affording means for accurately adjusting the stop device. By 5 turning the knurled head 67, the stop device 61 is adjustable inwardly or outwardly, with reference to the stop plate 60, and in this manner, the amount of horizontal movement of the threading tool can be accurately determined and finely adjusted.

10 The structure shown may be variously modified without departing from the underlying invention, and this application is intended to cover any changes or adaptations 15 coming within the intent of my invention or the scope of the following claims.

I claim:

1. In an insulator threading machine, the combination with a threading tool movable 20 in a plane vertically and horizontally at a right angle to its vertical travel, of means for effecting such horizontal movement, said means being automatically brought into operation at a predetermined point in the 25 vertical travel of the threading tool.

2. In an insulator threading machine, the combination with a threading tool movable in a plane vertically and horizontally at a right angle to its vertical travel, of means 30 for effecting such horizontal movement, and devices connecting said means with the threading tool whereby said horizontal movement takes place after the tool reaches the limit of its downward travel or before 35 commencing its upward travel.

3. In an insulator threading machine, the combination with a threading tool movable vertically and horizontally at a right angle to its vertical travel, of means for adjust- 40 ably limiting said horizontal movement.

4. In an insulator threading machine, the combination with a threading tool movable vertically and horizontally, of a stop device 45 adjustable to different positions for varying the extent of said horizontal movement, and fine-adjustment means controlling the position of said stop device.

5. In an insulator threading machine, the combination with a threading tool movable 50 vertically and horizontally, of means for effecting said horizontal movement, and an elevating device connected to the threading tool and to said horizontal actuating means and acting initially to permit movement of the threading tool to its lowermost position and thereafter bring into operation said horizontal actuating means for moving the tool horizontally.

6. In an insulator threading machine, the combination with a threading tool movable 60 vertically and horizontally, means for effecting said horizontal movement, and an elevating device including a vertically movable pulley, and a flexible connection passing over said pulley and having one end con-

nected to the threading tool and its other end connected to said horizontal actuating means.

7. In an insulator threading machine, the combination with a threading tool movable 70 vertically and horizontally, of actuating means for effecting said horizontal movement, said actuating means being spring actuated and including a control member which normally holds such parts inoperative, 75 and an elevating device including a pulley, and a flexible member passing around said pulley and having one end connected to the threading tool while its opposite end is connected to said control member, whereby the 80 latter is released to permit operation of the horizontal actuating means when the threading tool reaches its lowermost position.

8. In an insulator threading machine, the combination with a rotary threading tool 85 movable vertically and horizontally, of means for effecting such horizontal movement while the tool is rotating, said means being automatically brought into operation at a predetermined point in the vertical 90 travel of the threading tool.

9. In an insulator threading machine, the combination with a rotary threading tool movable vertically and horizontally, of fine- 95 adjustment means for adjustably limiting said horizontal movement.

10. In an insulator threading machine, the combination with a rotary threading tool movable vertically and horizontally, of means for effecting such horizontal movement, said means being automatically brought into operation at a predetermined point in the vertical travel of the threading tool, and fine-adjustment means for adjust- 100 ably limiting such horizontal movement. 105

11. In an insulator threading machine, the combination with a rotary threading tool movable vertically and horizontally, of means for effecting said horizontal movement while the tool is rotating, and an elevating device connected to the threading tool and to said means and acting initially to permit movement of the threading tool to its lowermost position, and thereafter bring into operation said horizontal actuating 110 means for moving the tool horizontally. 115

12. In an insulator threading machine, the combination with a rotary threading tool movable vertically and horizontally, of means for effecting said horizontal movement while the tool is rotating, an elevating device connected to the threading tool and to said means and acting initially to permit movement of the threading tool to its lowermost position and thereafter bring 120 into operation said horizontal actuating means for moving the tool horizontally, and fine-adjustment means for adjustably limit- 125 ing said horizontal movement.

13. In an insulator threading machine, the 130

- combination with a rotary threading tool movable in a plane vertically and horizontally at a right angle to its vertical travel, of 10
movable in a plane vertically and horizontally, of means for effecting such horizontal movement automatically at a predetermined point in the vertical travel of the threading tool.
- 5 14. In an insulator threading machine, the combination with a rotary threading tool
- movable in a plane vertically and horizontally at a right angle to its vertical travel, of 10
means for effecting such horizontal movement automatically at a predetermined point in the vertical travel of the threading tool.
- In witness whereof, I have hereunto signed my name.

CORNELIUS VAN DYKE BENNETT.
